UNITED STATES PATENT OFFICE

1,964,833

PAD BOX

William D. Thomas, Lynnfield, Mass., assignor to
 United Shoe Machinery Corporation, Paterson,
 N. J., a corporation of New Jersey

Application August 9, 1933, Serial No. 684,414

4 Claims. (Cl. 12—33)

This invention relates to pad boxes for use in applying pressure to shoes and is illustrated as embodied in a pad box for use in cement-attaching soles to shoes with the aid of a machine such as that shown in United States Letters Patent No. 1,897,105, granted February 14, 1933, on the application of Milton H. Ballard.

The pad box used in connection with sole attaching machines such as that shown in the Ballard patent comprises a fluid-filled receptacle having a dilatable or distortable sole and shoe receiving wall, and the machine itself is provided with shoe and last engaging abutments which act as pressure sustaining members and cooperate with the distortable wall to apply pressure to a shoe and sole, thereby forcing the sole into close contact with the shoe bottom. The distortable wall, when viewed from the side, has a contour generally resembling the profile of a shoe bottom. 15 As explained in the Ballard patent, the pad box is placed on the sole attaching machine, a cemented sole and a shoe are positioned on it, a preliminary pressure is applied to the shoe to set it firmly in position on the pad box, and then an operative pressure is applied. 20

In order to render the pad box properly applicable to shoes of varying sizes, the operative surface of the pad is necessarily much greater than the sole area of many of the shoes that are to be operated on. That part of the distortable wall of the pad which is not covered by the shoe tends to bulge up around the shoe when the operative pressure is applied, thus, in some cases tending to impart an undesirable curvature to the marginal portion of the sole. Such an effect is especially undesirable at the toe of the shoe, and has been avoided by the provision of a so-called mask plate mounted in a slideway in the pad box just above the pad and manually adjustable therein so that its rear, recessed edge can be made to fit reasonably well around the toe of the shoe, and thus confine this part of the pad surface against upward movement relatively to the sole under the operative pressure. 35

It is an object of the present invention to provide an improved construction of pad box and mask plate having more convenient provision for effecting the above-mentioned longitudinal adjustment of the mask plate. To this end I have so arranged the mask plate as to be movable with the toe plunger when the plunger is adjusted longitudinally of the pad box so that the proper adjustment of the toe plunger relatively to the shoe will, of itself, carry the mask plate into proper relation to the toe of the shoe. I effect this

by a direct mechanical connection between the mask plate and the bail which carries the toe plunger. I do not herein claim broadly the connection of the mask plate with the plunger, this being the invention of Frank R. Merritt and being claimed in his application Serial No. 683,930, filed August 7, 1933. 60

In the illustrated embodiment of my invention I have connected the bail to the mask plate, which slides in a guide way in the pad box frame, by a link. 65

These and other features of the invention comprising certain combinations and arrangements of parts will be apparent from the following description of a preferred embodiment of the invention shown in the drawing, in which. 70

Fig. 1 is a plan view of the pad box; and Fig. 2 is a side elevation.

The frame 10 of the illustrated pad box is rectangular and open at top and bottom, and it is provided with a hinged bottom 12 through the raising of which the operative pressure is applied. The pad 14, which, as shown, is a rubber bag reinforced with fabric and filled with water, rests on this bottom and extends upwardly to the top 80 of the box. The upper, operative surface of the bag, when viewed from the side, has a profile resembling that of a shoe bottom. The rear pressure bail 16 is pivoted at each end as at 18 to members 20 slidable on the frame 10 and having notches 22 into any one of which a pivotal latch 24 mounted on the pad box frame can fall. The heel pressure plunger 26 is vertically slidable in a boss at the upper end of the bail 16, and is forced toward its uppermost position by a spring 28. It is provided with ratchet teeth 30 cooperating with a spring-pressed dog 32 to hold it down against the shoe when it has been pressed down in the preliminary pressure applying operation. 85

The front or toe bail 34 has its ends fixedly mounted on rods 36 sliding in guides on the frame 10 and is held in longitudinally adjusted position by a spring-pressed latch 38 engaging in one of a series of holes 40 in the pad box frame. The boss 42 at the upper end of this bail 34 is provided 95 with ratchet teeth 48 cooperating with a dog 50.

The mask plate 52 slides longitudinally of the pad box in a guideway formed between plates 54 and the upper surface of the frame 10 and is 105 at all times restrained from movement away from the top wall of the pad 14 by the plates 54. It has a notch at its rear end shaped generally like the toe of a shoe. The mask plate is provided with a pair of ears 56 each of which is connected 110

with the bail 34 by a link 58 pivoted to the mask plate at one end and to the bail at the other. Thus the adjustment of the bail 34 and plunger 46 longitudinally of the pad box causes corresponding adjustment of the mask plate 52 in its slide-way, and the horizontal distance between the mask plate and the plunger is maintained unchanged, so that the necessity for manual adjustment of the mask plate to accommodate shoes of varying lengths is avoided.

Having described my invention, what I claim as new and desire to secure by Letters Patent of the United States is:

1. A pad box comprising a frame, a flexible pad supported therein, a pressure transmitting bail longitudinally adjustable on the frame, a mask plate longitudinally slidably mounted in the frame above the pad, and a direct connection between the bail and the mask plate whereby longitudinal adjustment of the bail correspondingly adjusts the mask plate.

2. A pad box comprising a frame having a guideway extending longitudinally of the frame, a mask plate slidably mounted in the guideway, a pad supported in the frame below the mask plate, a pressure bail longitudinally adjustable on the frame, and a link connecting the bail and the mask plate whereby adjustment of the bail effects corresponding adjustment of the mask plate.

30

3. A pad box comprising a fluid-filled receptacle having a distortable shoe engaging wall, pressure sustaining means adjustable longitudinally of the receptacle, a mask plate overlying the distortable wall and mounted for longitudinal adjustment relatively thereto, means effective at all times to prevent movement of the mask plate away from said wall, and a connection between the mask plate and the pressure sustaining member whereby longitudinal adjustment of the pressure sustaining member correspondingly adjusts the mask plate.

4. A pad box for use in cement attaching soles to shoes comprising a receptacle having a distortable wall formed and arranged to receive a sole and shoe, a mask plate overlying the distortable wall adjacent to the toe of a shoe operatively positioned on the pad and mounted for longitudinal adjustment relatively thereto but restrained against movement therefrom, the inner edge of said mask plate being curved to conform approximately to the contour of the toe of a shoe, a pressure sustaining bail carried by the pad box and mounted for adjustment longitudinally thereof, and a link connecting the bail and the mask plate whereby adjustment of the bail longitudinally of the pad box effects a corresponding adjustment of the mask plate.
